RICHARD T. NEWTON, OF NUTLEY, AND INGLIS M. UPPERCU, OF NEWARK, NEW JERSEY.

INTERNAL-COMBUSTION ENGINE.

1,148,118.

Specification of Letters Patent. Patented July 27, 1915.

Application filed November 21, 1913. Serial No. 802,227.

To all whom it may concern:

Be it known that we, RICHARD T. NEWTON and INGLIS M. UPPERCU, citizens of the United States, residing, respectively, at 5 Nutley, in the county of Essex and State of New Jersey, and at Newark, in the county of Essex and State of New Jersey, have invented certain new and useful Improvements in Internal-Combustion Engines; and we do 10 hereby declare the following to be a full, clear, and exact description of the invention, such as will enable others skilled in the art to which it appertains to make and use the same, reference being had to the accompanying drawings, and to characters of reference marked thereon, which form a part of this specification.

The present invention relates, generally, to improvements in internal combustion or 20 explosive engines; and, the invention has reference, more particularly, to an improved construction of engine, combining with the cylinder thereof a novel advancing and retarding exhaust and compression control 25 valve-mechanism, which will operate to either reduce or increase the amount and time of compression of the explosive mixture in the firing-chamber, and simultaneously advance or retard the time of the 30 exhaustion from the firing-chamber of the burnt or exploded gases.

The invention has for its principal object to provide, in connection with the cylinder of an internal combustion or explosive engine, a normally operated valve-mechanism 35 for controlling, between maximum and minimum limits, the compression of the fuel mixture in the firing-chamber, and the exhaustion of the burnt gases after firing or 40 ignition.

Another object of the present invention is to provide, in connection with the fuel intake of the engine, means for throttling the delivery of explosive mixture by the carbureter, the same being so connected with the operating means of said novel valve-mechanism, above referred to, as to be simultaneously or synchronously operated in company therewith.

A still further object of the present invention is to provide, in connection with the usual commutating device for controlling the timing of the delivery of the electric ignition current to the spark-plug introduced 55 within the firing-chamber, means for con-

necting with the operating means of said novel valve-mechanism, above referred to, said commutating device, so as to synchronize its operations to the operations of said valve-mechanism and said fuel throttling means.

Other objects of the present invention, not at this time more particularly enumerated, will be clearly understood from the following detailed description of the same.

With the various objects of the present invention in view, the same consists, primarily, in the novel construction of internal combustion engine hereinafter set forth; and, the invention consists, furthermore, in the novel arrangements and combinations of the various devices and parts, as well as in the details of the construction of the same, all of which will be more fully described in the following specification, and then finally embodied in the clauses of the claims, which are appended to and which form an essential part of this specification.

The invention is clearly illustrated in the accompanying drawings, in which:

Figure 1 is a side elevation of an internal combustion engine, made according to and embodying the principles of the present invention; Fig. 2 is a vertical longitudinal cross section of the same, taken on line 2—2 in said Fig. 1; and Fig. 3 is a detail vertical longitudinal section, taken on line 3—3 in said Fig. 2, looking in the direction of the arrow *x*.

Similar characters of reference are employed in all of the above described views, to indicate corresponding parts.

Referring now to the drawings, the reference character 1 indicates a complete internal combustion engine made according to and embodying the principles of the present invention, the same comprising a crank-casing 2, the lower half, or separable part, 3 of which is connected therewith in any suitable manner. Mounted in connection with said crank-casing 2, and secured in said connection in any suitable or in the usual manner, is a cylinder-member 4, the upper interior portion 5 of which provides the usual firing-chamber. The walls of said cylinder-member 4 are provided with the usual internal passages 6, through which cool water is introduced and circulated to provide the usual water-jacket surrounding the firing-chamber.

Journaled in the bearing-ports 7, which

65

90

95

100

105

110

are formed in connection with the crank-casing 2 and its lower half 3, is a crank-shaft 8, to the crank-portion 9 of which is connected one end of the pitman 10. The 5 other end of said pitman is connected with the journal or cross-pin 11 of a piston 12 which is slidably arranged within said cylinder-member 4, so as to reciprocate therein. Said piston 12 is hollow and open at its 10 lower end, so that its interior is in communication with the interior of said crank-casing. Formed in the wall of said cylinder-member 4, and located in any suitable or convenient part thereof, is a vertical by-pass 15 passage 13, the lower end of which terminates in a port or opening 14, opening into the lower part of the interior of said cylinder-member 4. The upper end of said by-pass passage 13 terminates in an enlarged 20 portion 15, in the mouth of which is seated a disk-valve 16, the downwardly depending stem 17 of which is slidably disposed in a socketed boss 18 formed in connection with the wall of said by-pass passage. Said enlarged 25 portion 15 of said by-pass passage 13 communicates with the firing-chamber 5 by means of a port or opening 19. Said disk-valve 16 is movable vertically so as to lift from its seat under the pressure of the gas 30 rising through said by-pass passage 13, the force of gravity tending to return said disk-valve to its seat, and maintaining the same in closing relation to said by-pass passage against the return of the gas therethrough 35 as the piston 12 compresses the gas within the said firing-chamber 5. The said cylinder-member 4 is provided, at a conveniently located point in its lower portion, with a gas intake port 20. Secured to the exterior of 40 said cylinder-member 4, so as to register with said gas intake port 20, is a gas conduit 21, which is connected with and leads from any desirable constriction or design of carbureter 22, in which the fuel mixture is 45 generated. Said gas intake port 20 is so located that, as the piston 12 moves upwardly in the cylinder-member 4, the same is uncovered, and the suction created within the crank-casing by the rising piston draws into 50 the crank-casing a charge of the fuel-mixture from said carbureter. The said piston 12 is provided in its wall, usually at a point adjacent to its upper end, with an opening or port 23, which, as the piston descends, 55 registers with the lower port or opening 14 of said by-pass passage 13, so that the fuel-mixture compressed within the crank-casing by the descent of said piston is caused to flow into said by-pass passage 13, there- 60 by lifting said disk-valve 16, so that said fuel mixture may pass through said port or opening 19 into the firing-chamber 5, wherein it is compressed by the rising piston preparatory to ignition of the same whereby 65 it is exploded to produce the power impulse.

The said cylinder-member 4 is further provided in its wall with a main exhaust port 24, the same being preferably located in a plane above the heretofore mentioned gas intake port 20. Also formed in the wall of 70 said cylinder-member 4 are a plurality of auxiliary exhaust ports 25, 25', 25'' and 25'', the same being disposed in vertical alinement one above the other, and all above said main exhaust port 24. Instead of said 75 plurality of exhaust ports, however, we may have the same connected in the form of an elongated single opening or slot.

The reference character 26 indicates a suitable exhaust conduit, the same being secured in any suitable manner to said cylinder-member 4, so as to register its inner end in communication with said main exhaust port 24. Connected with said exhaust conduit 26, and preferably forming an integral 80 part thereof, is a valve-casing 27, the same being formed with a hollow cone-shaped seat or chambered portion 28. The wall of said valve-casing 27 is provided with a plurality of openings 29, 29', 29'' and 29'', 90 which lead into said chambered portion 28, and which respectively register with said auxiliary exhaust ports 25, 25', 25'' and 25'', so that the latter will discharge into 95 said chambered portion 28. It will also be understood that said openings 29, 29', 29'' and 29'' may be connected in the form of an elongated single opening or slot, when the auxiliary port is so formed. Rotatably seated in said cone-shaped seat or chambered portion 28 is a hollow cone-shaped 100 rotatable valve-member or gate 30, the same being open at its lower end, as at 31, so as to communicate with the interior of said exhaust conduit 26. Said valve-member or gate 30 is provided with a centrally disposed 105 and upwardly extending stem 32, the same being journaled in an opening 3 formed in the upper portion of said valve casing 27. Secured to the exteriorly projecting end of 110 said valve-stem 32 is the hub-portion 34 of an outwardly extending lever-arm 35, by means of which the proper rotary movement may be imparted to said valve-member or gate. Mounted upon said valve-stem 32, beneath said hub-portion 34 is a washer 36, and positioned between said washer and the upper surface of said valve-casing 27 is a coil-spring 37, the tension of which serves 115 to press upwardly against said washer 36 and hub-portion 34 and thus exerts an upward pull upon said valve-member or gate 30 which maintains the same upon said seat or chambered portion 28. Said valve-member 120 has a triangular port or opening 38, one longitudinal edge of which is vertical as at 39, and the other or opposite longitudinal edge of which is inclined, as at 40, the said inclined edge converging with said vertical edge at the upper end of said port or open- 125

ing. When the valve is wide open, as shown in the drawings, all the exhaust ports 25, 25', 25'' and 25''' are in communication with said port or opening 38 of said valve-member or gate, and by rotating said valve-member or gate, so that said inclined marginal edge of the port or opening 38 is carried toward said exhaust opening or ports, the same may be successively closed against the passage of exhaust therethrough. In this manner it will be apparent that by any selected degree of opening or closing of said valve-member or gate by turning the same, one or more of said auxiliary exhaust ports 15 may be opened or closed. It will be apparent that when said valve-member or gate is positioned so as to shut off or close all of said auxiliary exhaust ports, the said main exhaust port 24 is alone in communication 20 with the firing chamber 5 of said cylinder-member. Under such a condition the piston begins to compress the charge of fuel mixture introduced into the firing-chamber the moment the same passes said main exhaust port 24 upon its upward stroke or movement, consequently a maximum compression of a maximum fuel charge is attained, and when said charge is ignited, the exhaustion is delayed until the piston, on its downward stroke or movement, again passes and 25 opens said main exhaust port 24, and thus the full or maximum power impulse derived from the expansion of the exploded fuel charge is utilized and available. When, 30 however, said valve-member or gate 30 is so positioned that it registers its port or opening 38 with the auxiliary exhaust port 25, the auxiliary exhaust ports 25', 25'' and 25''' remaining closed, it follows that said auxiliary exhaust port 25 is brought into communication with said exhaust conduit 26, consequently the amount of compression resulting from the rising of the piston in the firing-chamber 5 is reduced since the 35 compressing operation of the piston is delayed until said piston passes said auxiliary exhaust port 25, and from the same cause the time of exhaustion of the exploded fuel charge is advanced, so as to occur earlier 40 during the downward movement or stroke of said piston, by reason of the opening of said auxiliary exhaust port 25 in advance of the opening of said main exhaust port 24 by the downwardly passing piston. It follows, therefore, that by moving said valve-member or gate 30 to open successively said auxiliary exhaust ports, the compression stroke of said piston may be regulated and controlled between the maximum limit, 45 which is predicated upon the use of said main exhaust port 24 alone, and the minimum limit, which is predicated upon the use of all of the auxiliary exhaust ports in addition to said main exhaust port 24; and 50 in like manner the power impulse of the exploded fuel charge is likewise regulated and controlled between maximum and minimum limits, by the advancing of the time of exhaustion or discharge of the exploded fuel with relation to the downward movement 70 or stroke of the piston. Of course means must be provided for operating said valve-member or gate 30 to attain the results above pointed out, and since such means may be greatly varied in its detail construction, we do not limit ourselves to the means shown in the accompanying drawings and hereinafter described, but intend the same to be merely illustrative of one of a plurality of modes by which the desired result 75 may be attained.

As shown in the drawings, the said operating means consists of a rock-shaft 41, which may be suitably mounted in any convenient place exterior of the engine. 80 Fixed upon said rock-shaft 41 is a lever-arm 42, to the free end of which is pivotally secured one end of a connecting rod 43, the opposite end of which is pivotally connected with the free end of said lever-arm 35 which 85 is secured upon the stem 32 of said valve-member or gate 30. Fixed upon said rock-shaft 41 is an operating lever 44, which, of course, may be operated by hand or foot application as desired, the same, when operated, causing the oscillation of said rock-shaft 41 and lever-arm 42, the resultant movement being transmitted by said connecting-rod 43 to said lever-arm 35 and consequently said valve-member or gate 30. 90 Said operating lever 44 and the rock-shaft 41, together with the parts operated by and connected therewith, may be returned to normal initial position automatically by the tension of a spring-means 45 connected with the arm 46, or, when such an arrangement is desired, the return to initial position may be accomplished by the manual reverse operation of said operating lever 44. 95

When it is desired to reduce the amount 100 of compression of the fuel charge and the strength of the power impulse of the exploded fuel charge, by means of the operation of the auxiliary valve mechanism as above described, it is also desirable to reduce proportionally the volume of fuel mixture delivered from the carburetor to the firing-chamber simultaneously, and to this end a valve means is provided in the gas delivery conduit 21, together with means 105 for simultaneously operating the same in company with said auxiliary valve-mechanism. Said valve means comprises a spindle 47, which is journaled in the walls of said gas delivery conduit 21, so as to extend 110 transversely therethrough. Mounted or fixed upon said spindle 47, within said gas delivery conduit 21, is a butter-fly valve-disk 48, which may be turned across said conduit 21 so as to obstruct in varying degrees 115

120

125

130

135

the free passage of the fuel mixture therethrough. Said valve-disk 48 may be provided with a marginal depression or cut-away portion 49, which assures the passage 5 of a minimum amount of the fuel mixture thereby, even though said valve-disk be entirely closed. Secured to the exteriorly projecting end of said spindle 47 is a lever-arm 50, and secured externally to the walls of 10 said conduit 21 are outwardly projecting stop-pins 51 and 51', which when engaged by said lever-arm 50 respectively stop the same, and serve to check the movement of said valve-disk 48 when the same reaches 15 either its completely closed or completely open position. Pivottally connected with the free end of said lever-arm 50 is a knuckle-joint 52, through which extends one end of a connecting-rod 53, the same being capable of a sliding movement therethrough. A collar or nut 54 fixed upon the extreme end of said connecting-rod prevents the withdrawal of said connecting-rod from said knuckle-joint. Also fixed upon said connecting-rod 53, upon the opposite side of 25 said knuckle-joint is another collar 55, between which and said knuckle-joint is arranged a coil-spring 56. The opposite end of said connecting-rod 53 is pivotally secured to the free end of a lever-arm 57, which is also fixed upon said rock-shaft 41 so as to be oscillated thereby simultaneously with the operation of said auxiliary valve-mechanism. When the operating lever 44 30 is manipulated, the movement of said rock-shaft 41 and lever-arm 57 is transmitted through said connecting-rod 53 to said lever-arm 50, so that as said auxiliary valve-mechanism is operated to open said auxiliary exhaust ports, the said butter-fly valve-disk 48 is simultaneously caused to move into closing relation to said conduit 21, and thereby reduce the amount of fuel mixture passed therethrough. Since, however, said 35 valve-disk is preferably arranged to reach its completely closed position in advance of said valve-member or gate 30 reaching its completely opened position, and since both mechanisms are operated from the same 40 source of power application, it is apparent that said connecting rod 53 continues to move after the valve-disk 48 is completely closed and stopped from further movement, hence the necessity of some device such as 45 the slidable connection of said connecting-rod 53 with the knuckle-joint 52 and the coil-spring 56, for as the lever-arm 50 and its knuckle-joint 52 comes to rest, the connecting-rod 53 continues to move, thereupon 50 sliding through said knuckle-joint and compressing the coil-spring 56, which consequently maintains said valve-disk 48 closed, while said connecting-rod 53 is recovering 55 this additional movement during the reverse operation of the mechanism, or the return of

the mechanism to normal initial positions. It will be apparent that, from the novel correlation and coöperation of said auxiliary valve mechanism and said fuel control valve mechanism, simultaneously with the reduction of the amount of compression and strength of power impulse as the latter is controlled by early exhaustion, we also reduce the quantity or volume of fuel mixture delivered to the firing-chamber 5, thus providing for an exceedingly high degree of economy in fuel consumption, together with a highly efficient control of the engine power and operation.

In addition to the simultaneous control 80 of fuel charge supply, compression and exhaustion, as provided for by means of the above described mechanisms, it is also desirable to provide, in simultaneous control and coöperation therewith, means for advancing and retarding the time of delivery of the electric ignition current to the spark-plug 58, which is connected as usual with the cylinder-member 4, and presented within the firing-chamber 5. To this end the 85 usual commutator device 59 is provided, the shaft 60 of which is driven, in properly timed relation, by the crank-shaft 8 through the gearing 61. Said commutator 59 is provided with the usual outwardly extending 90 arm 62, whereby its contact carrying member is shifted with relation to the rotary brush driven by its shaft 60, to advance or retard the closing of the ignition circuit to the spark-plug, all in the well known and 95 ordinary manner. Fixed upon said rock-shaft 41 is another lever-arm 63, to the free end of which is pivotally secured one end of a connecting-rod 63, the opposite end of 100 which is pivotally connected with said arm 62 of said commutator device 59, so that upon the operation of said auxiliary valve-mechanism and fuel supply reducing mechanism, there is accomplished a simultaneous and proportional retardation of the time of 105 ignition current delivery to the spark-plug 58.

We are aware that some changes may be made in the general arrangements and combinations of the several devices and parts, as 110 well as in the details of the construction of the same, without departing from the scope of the present invention as set forth in the foregoing specification. Hence, we do not limit our present invention to the exact arrangements and combinations of the various 115 devices and parts as described in the said specification, nor do we confine ourselves to the exact arrangements or details of the construction of the said parts as illustrated in 120 the accompanying drawings.

We claim:—

1. The combination with the cylinder provided with a main exhaust port of a plurality of auxiliary exhaust ports, means for 125

successively opening said auxiliary exhaust ports, fuel delivery means, means for controlling the passage of fuel through said delivery means, and mechanism for simultaneously operating said opening means of said auxiliary exhaust ports and said fuel control means.

2. The combination with the cylinder provided with a main exhaust port of an auxiliary exhaust port disposed in a plane above said main exhaust port, a movable gate cooperating with the outer end of said auxiliary exhaust port and adapted to open the same to various degrees between its closed and fully open condition whereby the time of exhaust expulsion may be varied relative to the piston movement, means for operating said movable gate, a fuel intake port, fuel delivery means, means for controlling the passage of fuel through said delivery means, and means for simultaneously operating said controlling means and said movable gate.

3. The combination with the cylinder provided with a main exhaust port of an auxiliary exhaust port disposed in a plane above said main exhaust port, a movable gate cooperating with the outer end of said auxiliary exhaust port and adapted to open the same to various degrees, means for operating said movable gate, a fuel intake port, fuel delivery means, means for controlling the passage of fuel through said delivery means, means for operating said controlling means, and a piston slidably arranged in said cylinder and adapted to control the opening of said main exhaust port, the inner end of said auxiliary exhaust port and said fuel intake port.

4. The combination with the cylinder provided with a main exhaust port and a fuel intake port of a plurality of auxiliary exhaust ports disposed in successive planes above said main exhaust port, a piston mounted to reciprocate within said cylinder and adapted to control the opening of said main exhaust port, the inner ends of said auxiliary exhaust ports, and said fuel intake port, a movable gate cooperating with the outer ends of said auxiliary exhaust ports and adapted to successively open the same, fuel delivery means communicating with said fuel intake port, means for controlling the passage of fuel through said delivery means, and mechanism for simultaneously operating said movable gate and said fuel control means.

5. The combination with the cylinder provided with a main exhaust port and a fuel intake port of a plurality of auxiliary exhaust ports disposed in successive planes above said main exhaust port, a piston mounted to reciprocate within said cylinder and adapted to control the opening of said main exhaust port, the inner ends of said

auxiliary exhaust ports and said fuel intake port, a movable gate cooperating with the outer ends of said auxiliary exhaust ports and adapted to successively open the same, fuel delivery means communicating with said fuel intake port, means for controlling the passage of fuel through said delivery means, a spark-plug in said cylinder, a commutator device for timing the delivery of electric ignition current to said spark-plug, means for controlling the operation of said commutator device, and mechanism for simultaneously operating said movable gate, said fuel control means and said commutator control means.

6. The combination with the cylinder provided with a main exhaust port and a plurality of auxiliary exhaust ports, disposed in successive planes above said main exhaust port, of an exhaust conduit registering with said main exhaust port, a valve-casing connected with said exhaust conduit and provided with openings registering with said auxiliary exhaust ports, a hollow valve-member rotatably mounted in said valve-casing, the interior of said valve-member being open to communication at its lower end with said exhaust conduit, said valve-member having a port constructed to successively open to communication with the interior of said valve-member said auxiliary exhaust ports when said valve-member is turned, and means for rotating said valve-member.

7. The combination with the cylinder provided with a main exhaust port and a plurality of auxiliary exhaust ports, disposed in successive planes above said main exhaust port, of an exhaust conduit registering with said main exhaust port, a valve-casing connected with said exhaust conduit and provided with openings registering with said auxiliary exhaust ports, a hollow valve-member rotatably mounted in said valve-casing, the interior of said valve-member being open to communication at its lower end with said exhaust conduit, said valve-member having a port constructed to successively open to communication with the interior of said valve-member said auxiliary exhaust ports when said valve-member is turned, said cylinder being further provided with a fuel intake port, a fuel delivery conduit registered with said fuel intake port, a butter-fly valve-disk rotatably mounted to extend transversely across said fuel delivery conduit, and mechanism for simultaneously operating said valve-member and said butter-fly valve-disk.

8. The combination with the cylinder provided with a main exhaust port and a plurality of auxiliary exhaust ports, disposed in successive planes above said main exhaust port, of an exhaust conduit registering with said main exhaust port, a valve-

6
casing connected with said exhaust conduit and provided with openings registering with said auxiliary exhaust ports, a hollow valve-member rotatably mounted in said 5 valve-casing, the interior of said valve-member being open to communication at its lower end with said exhaust conduit, said valve-member having a port constructed to successively open to communication with the 10 interior of said valve-member said auxiliary exhaust ports when said valve-member is turned, said cylinder being further provided with a fuel intake port, a fuel delivery conduit registered with said fuel intake 15 port, a butterfly valve-disk rotatably mounted to extend transversely across said

fuel delivery conduit, a spark-plug in said cylinder, a commutator device for timing the delivery of electric ignition current to said spark-plug, means for controlling the 20 operation of said commutator device, and mechanism for simultaneously operating said valve-member, said butterfly valve-disk, and said commutator control means.

In testimony, that we claim the invention 25 set forth above we have hereunto set our hands this 18th day of November, 1913.
